UNITED STATES PATENT OFFICE.

WILLIAM KUENZLE AND WILLIAM POEHLMANN, OF PHILADELPHIA,
PENNSYLVANIA.

HAT AND CLOTHES RACK.

SPECIFICATION forming part of Letters Patent No. 592,250, dated October 26, 1897.

Application filed January 29, 1897. Serial No. 621,175. (No model.)

To all whom it may concern.

Be it known that we, WILLIAM KUENZLE and WILLIAM POEHLMANN, citizens of the United States, residing in the city and county 5 of Philadelphia, State of Pennsylvania, have invented a new and useful Improvement in Hat and Clothes Racks, which improvement is fully set forth in the following specification and accompanying drawings.

10 Our invention consists of an improvement in hat and clothes racks embodying sectional brackets admitting of the reception or application and removal of the cross-rod which supports the hooks in a convenient and practical manner, provision being made for setting or adjusting the hooks and preventing rotation of the same and of the rod which supports them.

Figure 1 represents a perspective view of a 20 hat and clothes rack embodying our invention. Fig. 2 represents a side elevation of one of the brackets in separated condition and a section of the hook-supporting rod. Fig. 3 represents a perspective view of one 25 of the hooks, the adjacent portion of the supporting-rod, and the tightening or retaining nut therefor. Fig. 4 represents a top or plan view of the rack on a reduced scale, showing how the same is more particularly serviceable.

30 Similar letters of reference indicate corresponding parts in the several figures.

Referring to the drawings, A designates the side brackets of a hat or clothes rack, and B designates the cross-rod thereof, said rod carrying the hooks C, which latter are secured to bosses D, which freely receive said rod, whereby the hooks may be shifted and set nearer to or farther from each other, as desired, and the number of hooks may be increased or decreased according to requirements. On the end of the rod are the nuts E, which are screwed to the threaded ends F thereof for preventing displacement thereof. The brackets A are constructed of separate 45 sections G and H, the outer ends thereof being formed of half-sockets J to receive the adjacent portions of the rod B, the inner ends being provided with eyes K for securing the brackets to a wall or other place of applica-

tion. The half-sockets are connected with 50 the main portions of the brackets by the arms L, in which are vertical openings to receive the screw M, whereby the separate parts of the brackets may be clamped together or connected as one. It will be seen that when the 55 screw is removed the brackets are separated, and the lower section may then be placed and secured in position. The rod B is now seated on the lower half-socket J and the upper section of the bracket applied in place, its half-socket closing on the rod B, after which the screw is rotated, whereby the two arms are drawn together and with them the half-sockets, thus retaining the rod B in position. In 60 this manner the rod has been located in a convenient and practical manner, a feature appreciable where such a rod cannot be introduced endwise into the sockets of the brackets, and is likewise a matter of convenience to adjust the lower sections of the brackets 65 and then apply the rod, instead of necessarily holding, handling, or supporting the entire bracket at one time. The lower end of the section G has an L-shaped or angular portion N, which is in contact with an angular 70 portion N' of the section H, the base or horizontal portion of said angular portions being the arms L, which receive the clamping-screw 75 M in the openings in the same. It will also be noticed that the rod B is of angular form, 80 and the openings of the bosses D are also angular, the same being true of the inner faces of the half-sockets, whereby neither the rod nor the hooks are liable to rotation.

Having thus described our invention, what 85 we claim as new, and desire to secure by Letters Patent, is—

1. A hat and clothes rack consisting of side brackets each composed of two sections, each section having at its inner end means for securing it to a suitable support, and at its outer end an angular portion, both limbs of which contact with the angular portion of the other section, the horizontal limb of each of said angular portions having an angular-shaped opening forming a half-socket to receive a cross-bar, and an opening in rear of 90 said angular opening to receive a clamping- 95

screw, and a cross-bar held in said angular openings.

2. An angular rod and hooks with angular bosses freely supported on said rod, in combination with brackets formed in sections, each being provided at one end with an attaching device and at the other end with a half-socket and a screw engaging with proper

portions of said sections for closing the half-sockets as one on said rod.

WILLIAM KUENZLE.
WILLIAM POEHLMANN.
